UNITED STATES PATENT OFFICE.

CLEM S. CLARKE, OF SHREVEPORT, LOUISIANA.

CASING-HEAD.

1,400,940.

Specification of Letters Patent. Patented Dec. 20, 1921.

Application filed August 28, 1920. Serial No. 406,554.

To all whom it may concern:

Be it known that I, CLEM S. CLARKE, a citizen of the United States, residing at Shreveport, in the parish of Caddo and State 5 of Louisiana, have invented new and useful Improvements in Casing-Heads, of which the following is a specification.

This invention relates to attachments for the casings of oil, gas, or other wells, and 10 has for its object the provision of a head adapted to be secured upon the upper end of a well casing and provided with wedge actuated clamping means for holding a pipe or tubing within the head and casing, 15 whether the tubing be desired for the purpose of pumping and to inclose digger rods, whether swabbing is desired, or whether the tubing be desired as a housing for drill rods or the like.

20 An important object is the provision of a device of this character including a separable clamping member adapted to grip the pipe or tube and wedged into engagement with the pipe or tube by the weight of the 25 latter, the clamping member having inclined sides and engaging within an inclined bore in the head.

An additional object is the provision of a device of this character which may be 30 quickly and easily applied and which is consequently a great time and labor saver; which will remain firmly in position until positively disengaged, which will be very efficient in its holding action, durable in service, 35 and a general improvement in the art.

With the above and other objects and advantages in view, the invention consists in the details of construction to be hereinafter more fully described and claimed and illustrated in the accompanying drawings in 40 which—

Figure 1 is a longitudinal sectional view through my device in position upon a casing head and showing it holding tubing,

45 Fig. 2 is a similar view taken at right angles to Fig. 1,

Fig. 3 is a plan view, and

Fig. 4 is a cross sectional view on the line 4—4 of Fig. 2.

50 Referring more particularly to the drawings, the letter A designates a well casing and B designates tubing. In carrying out my invention I provide a member 10 which is hollow and which is internally threaded at its lower end to be screwed upon the upper

end of the casing A. Adjacent its end portion the body 10 is formed with a flange 11 engaging upon the top of the casing A. At its upper end the body 10 is formed with a cylindrical recess 12 providing an upstanding flange 13 and this recess leads into the bore 14 of the body, this bore having its upper end tapered, as shown at 15. The body is formed at diametrically opposite points with threaded holes 16. The purpose of the bore 14 is to permit the passage of the tubing.

The device further including a clamping member comprising a plurality of sections 17 which placed together form a truncated cone and these sections have their inner faces toothed, as shown at 18, and their outer faces inclined or tapered, as shown at 19, for conforming engagement within the tapered portion 15 of the bore. The sections 20 are provided at their tops with handles 21 whereby they may be lifted out of the body 10. These sections 17 are adapted to be placed in embracing engagement upon the tubing B and to fit within the tapered portion 15 of the bore so that the engagement of the inclined wall of the bore portion 15 will force the members 17 inwardly into clamping engagement with the tubing. After the parts are thus arranged the weight of 85 the tubing pulling upon the sections 17 will tend to move them downwardly and consequently exert a still greater clamping action.

After the sections 17 are in place within the bore portion 15 the washer 21 is placed 90 over them within the recess 12 and on top of this washer is placed a second washer 22 which is engaged and held in place by a plurality of screws or bolts 23 which are threaded through the flange 13 and which 95 engages over the top of the washer 22. As illustrated in Figs. 1 and 3, the upper face of the ring or washer 22 is beveled and the ends of the set screws 23 are beveled and afford a wedging action upon adjusting of 100 these screws. This wedging action between the screws and the ring or washer 22 forces the clamping element 17 downwardly into more positive engagement with the well tubing. The purpose of this arrangement is to 105 prevent upward displacement of the sections 17 from any cause and consequent loosening of the other grip upon the tubing.

From the foregoing description and a study of the drawings it will be apparent 110

that I have thus provided a simply constructed and consequently inexpensive casing head which is so constructed that it will positively grip tubing and hold the latter firmly in position within the casing so as to prevent any possible displacement regardless of the operations within the tubing.

While I have shown and described the preferred embodiment of my invention, it is of course to be understood that I reserve the right to make such changes in the form, construction, and arrangement of parts as will not depart from the spirit of the invention or the scope of the subjoined claims.

Having thus described my invention, I claim:

1. A well casing head comprising a cylindrical body having a longitudinal bore, the upper end of which is frusto-conical, co-acting tapered gripping elements arranged in the frusto-conical end of the bore and provided with serrations on their inner faces adapted to engage a well tube passing longitudinally through the casing head, an upstanding flange on the upper end of the casing head, a ring engaging the ends of the

clamping elements and having its upper face beveled, and set screws carried by the flange and having their inner ends beveled and adapted to engage the beveled surface 30 of the ring whereby to force the ring downwardly against the clamping elements to force the latter downwardly into positive engagement with the well tubing.

2. A well casing head comprising a cylindrical body having a longitudinal bore, the upper end of which is frusto-conical, co-acting tapered gripping elements arranged in the frusto-conical end of the bore and adapted to engage a well tube passing longitudinally through the casing head, a chamber above the frusto-conical end of the bore into which the upper ends of the clamping elements extend, a member in the chamber engaging the upper ends of the clamping elements, and means in the chamber for forcing the member downwardly against the clamping elements whereby to force the latter into positive engagement with the well tubing.

In testimony whereof I affix my signature.
CLEM S. CLARKE.
